UNITED STATES PATENT OFFICE.

CHARLES E. FLYNN, OF DE BEQUE, COLORADO.

TOY MOVING-PICTURE MACHINE.

1,383,095.

Specification of Letters Patent. Patented June 28, 1921.

Application filed April 10, 1920. Serial No. 372,871.

To all whom it may concern:

Be it known that I, CHARLES E. FLYNN, a citizen of the United States, residing at De Beque, in the county of Mesa and State 5 of Colorado, have invented new and useful Improvements in Toy Moving-Picture Machines, of which the following is a specification.

The object of the invention is to provide 10 a cut-out toy suitable for publication in newspaper or newspaper supplements, magazines, books and the like, and designed when cut out and set up in accordance with directions, to serve as a means of exhibiting after 15 the manner of commercial moving picture machines, a progressive scene in connection with a web or tape serving in lieu of a film and adapted also to be produced in cut-out sectional form for arrangement in operative 20 condition by the purchaser of the paper or magazine as a source of entertainment or as a means of conveying instructive information, and to this end the invention consists in a construction and combination of 25 parts of which a preferred embodiment is shown in the accompanying drawing, wherein:

Figure 1 is a plan view of the blank from 30 which the frame of the machine is constructed.

Fig. 2 is a side view of the device in its cut out and set up condition.

Fig. 3 is a plan view of the same.

Fig. 4 is a section on the plane indicated 35 by the line 4-4 of Fig. 3.

Fig. 5 is a transverse section on the plane indicated by the line 5-5 of Fig. 2.

Fig. 6 is a plan view of the blank from 40 which the web or tape is formed.

In the illustrated embodiment of the invention the blank forming the main portion 45 of the cut out, from which the frame of the machine is produced, consists of a base 10 from which extend the foldable side members 11, adapted to be folded on the dotted lines 12 of Fig. 1 and respectively provided with parallel extensions 13 adapted to be folded upon the dotted lines 14 to overlap terminally as indicated in Figs. 3 and 4 50 when the device is set up, the overlapping extremities being secured together by paste or other adhesive, and preferably being gummed as shown at 15 to facilitate this connection. These terminally attached extensions or arms 13 thus form a transverse brace

between the side members 11 which are designed for arrangement in planes perpendicular to that of the base 10.

Also extending from the base or body portion of the blank near the end opposite from 60 the side members 11 are ears 16 which are adapted to be folded upon the dotted lines 17 to lie in contact with the upper surface of the base member 10 as shown in Figs. 2 and 3 and also secured by paste or other adhesive and preferably having their originally upper surfaces gummed as indicated by the feed lines in Fig. 1.

Extending from one side of the base or body portion of the blank preferably adjacent to the ears 16 is an arm 18 which is adapted to be folded upon the dotted lines 19 to overlie the upper surface of the base 10 as indicated in Figs. 2, 3 and 5, the free terminal being secured in place to the adjacent edge of the base by means of a wire clip such as a paper fastener 20, it being obvious that other means may be employed for this purpose as may be found convenient by the operator. The cut-out element 21 consists of a substantially rectangular body portion having edge projections 22 and terminal projections 23, the latter forming trunnions provided with reduced portions or necks 24, adapted to be mounted in bearing slots 25 which are formed in the extremities of the side members 11 when the frame is set up 80 as shown in Figs. 2 and 3, and 26 and 27 are cut-out guide members adapted to be engaged respectively with holes or openings 26^a and 27^a punched in the side members 90 near the fold lines 12.

While it is obvious that any extended strip or tape carrying a pictorial display as of mobile objects arranged serially and progressively to indicate successive positions or postures of the object may be used in connection with the apparatus, it is designed that the same shall be published as a cut-out adjunct to the features above described, 95 as shown in Fig. 6 of the drawing wherein the succession of pictures are arranged upon strip sections indicated at 28 and adapted after being cut out to be terminally attached in series, for which purpose the extremities 100 thereof are gummed as shown at 29, the width of the sections and hence of the continuous strip when the sections have been secured together, serially, being such as to fit in the spaces between the guide projec- 105 110

- tions 22 of the reel member formed by the substantially rectangular body portion 21 having the terminal trunnions 23, and when the reel member has been mounted as above 5 noted in the bearings formed by the slot 25 in the side members of the main blank, the strip forming the web or tape may be extended thereover and between the guide members 26 and 27 and the free or front 10 end of the sets or series or may be extended under the arm 18 and over the ears 16, said arm 18 forming a tension member to regulate the movement of the strip as it is drawn toward the operator, thus causing the rotation of the reel and the successive exposure 15 of the pictorial representations upon the web or tape. As shown clearly in Fig. 2 the continuous and relative rapid feeding of the web or tape will cause a sufficiently rapid 20 succession of exposures of the picture elements, by reason of the turning over of the reel, to give the impression of a moving picture under conditions which will prove both entertaining and instructive so that 25 the device will have particular value as a toy for juvenile construction and amusement to which different series of pictures may readily be applied or adapted as the ingenuity of the operator is stimulated.
- 30 Having thus described the invention what is claimed is:
1. A toy cut-out comprising a blank having a base and connected foldable side members, provided with registering bearings, 35 a reel having a flat body and terminal trunnions to engage said bearings and a flexible strip engageable over the reel and having mobile objects depicted thereon in progressively different positions.
  - 40 2. A toy cut-out comprising a blank having a base and connected foldable side members provided with registering bearings, a reel having a flat body and terminal trunnions to engage said bearings, and a flexible strip engageable over the reel and having mobile objects depicted thereon in progressively different positions, and arranged at 45 intervals adapting them for successive exposure in traversing the reel.
  - 50 3. A toy cut-out comprising a blank having a base and connected foldable side members provided with registering bearings, a reel having a flat body and terminal trunnions to engage said bearings, and a flexible 55 strip having mobile objects depicted thereon in progressively different positions, and arranged respectively in consecutive spaces corresponding with the width of the reel body.
  - 60 4. A toy cut-out comprising a blank having a base and connected foldable side members provided with registering bearings, a reel having a flat body and terminal trunnions to engage said bearings, and a flexible
- strip for traversing said reel, consisting of 65 terminally attachable cut-out sections.
5. A toy cut-out comprising a blank having a base and connected foldable side members provided with registering openings, a reel having a flat body and terminal trunnions to engage said bearings, and a flexible strip for traversing said reel, consisting of 70 terminally attachable cut-out sections having serially arranged pictures including mobile objects depicted on each section in progressively different positions.
6. A cut-out comprising a blank having a base and opposite flexible side members provided with transversely registering bearings, said side members having terminally 80 attachable extensions to provide a transverse brace between the side members, a reel having a flat body and terminal trunnions for reception by said bearings and a flexible strip engageable over the reel and having 85 mobile objects depicted thereon in progressively different positions.
7. A toy cut-out comprising a blank having a base provided with laterally foldable 90 guide ears and opposite foldable side members provided with transversely registering bearings, said side members having terminally attachable extensions to provide a transverse brace between the side members, a reel having a flat body and terminal trunnions for reception by said bearings and a flexible strip engageable over the reel and having 95 mobile objects depicted thereon in progressively different positions.
8. A cut-out comprising a blank having 100 a base provided with a foldable tension element for arrangement in parallelism with the base, and opposite foldable side members provided with transversely registering bearings, said side members having terminally 105 attachable extensions to provide a transverse brace between the side members, a reel having a flat body and terminal trunnions for reception by said bearings, and a flexible strip engageable over the reel and having 110 mobile objects depicted thereon in progressively different positions.
9. A cut-out comprising a blank having a base and opposite foldable side members provided with transversely registering bearings, side members having terminally 115 attachable extensions to provide a transverse brace between the side members, a reel having a flat body and terminal trunnions for reception by said bearings, transverse guide 12 members for terminal engagement with the side members in parallelism with the axis of the reel, and a flexible strip engageable 125 over the reel and having mobile objects depicted thereon in progressively different positions.
- In testimony whereof I affix my signature.
CHARLES E. FLYNN.
